UNITED STATES PATENT OFFICE.

ALBERT S. GRAY, OF GRAND RAPIDS, MICHIGAN.

HYDRAULIC AIR-PUMP.

No. 907,341.

Specification of Letters Patent. Patented Dec. 22, 1908.

Application filed January 15, 1908. Serial No. 410,986.

To all whom it may concern:

Be it known that I, ALBERT S. GRAY, a citizen of the United States, residing at Grand Rapids, in the county of Kent and 5 State of Michigan, have invented a new and useful Hydraulic Air-Pump, of which the following is a specification.

The object of this invention is to provide an improved form of valve for use with a 10 hydraulic air pump.

A further object of the invention is to provide an improved form of hydraulic air pump especially arranged for use with the valve.

With these and other objects in view, as 15 will more fully hereinafter appear, the invention consists in certain novel features of construction and arrangement of parts, hereinafter fully described, illustrated in the accompanying drawings, and particularly 20 pointed out in the appended claims, it being understood that various changes in the form, proportions, size and minor details of the structure may be made without departing from the spirit or sacrificing any of the ad- 25 vantages of the invention.

In the accompanying drawings:—Figure 1 is an elevation of an air pump constructed in accordance with the invention, parts being broken away in order to more clearly illustrate the details. Figs. 2 and 3 are detail sectional views of the valve for controlling the fluid under pressure that is employed for actuating the pumping devices.

Similar numerals of reference are employed to indicate corresponding parts throughout the several figures of the drawings.

The air pumping apparatus comprises a pair of air pumps 10 and 11, each of which 40 consists of a lower water tank 15 and an air bell 16. Arranged in one of the tanks is a vertical cylinder 17, and in the other tank is a cylinder 18. Each of these tanks is provided with a piston 19 that is connected by a rod 20 to the top of the air bell, and when fluid under pressure is admitted to the lower end of the cylinder, the piston will be forced up and will carry with it the air bell, air being drawn in to the upper portion of the bell 45 through a one-way valve 21, which automatically closes as soon as the bell starts to descend. Arranged between the two cylinders is a valve casing 25 that is divided by a central block 26 into two chambers 27 and 50 28. The upper chamber 27 communicates with the lower end of the cylinder 18 through

a pipe 29, and the lower chamber 28 communicates with the lower end of the cylinder 17 through a pipe 30. Leading into one end of the valve casing is a water pipe 32, through which water is forced from any suitable source of supply, and leading from the opposite end of the cylinder is a discharge pipe 33 that is connected to the upper portions of the air pump tanks, so as to replenish the water therein. The waste water flows off through a discharge pipe 34. Arranged in the valve casing are two valves 37 and 38, the valve 37 having two ports 39 and 40, and the valve 38 having two ports 41 and 42. 60 These valves are connected by rods 43 to a three armed lever 44 that is pivoted on a standard 45 carried by the valve casing. The central arm of the lever extends up and is provided with a weight 46 that operates to 65 move the valves to the final position as soon as the weighted arm of the lever is shifted beyond the vertical plane of the lever pivot. 70

At any suitable point above the air pumps are arranged a series of sheaves 50, and over 75 these are guided two chains or cords 51 and 52. One end of each cord or chain is connected to one of the air pump bells, and the opposite end to one of the arms of the valve operating lever 44, so that as the bells move, 80 the valves will be shifted for the purpose of controlling the flow of the water to and from the cylinders 17 and 18. 85

In the operation of this portion of the mechanism, the valve is in the position 90 shown in Fig. 3, and the water entering under pressure through the pipe 32 will flow through the valve port 40 to the chamber 27, and thence through pipe 29 to the lower end of the cylinder 18, thereby raising the piston 95 in said cylinder, and forcing the air pump bell up to its highest point. During this operation, the opposite bell is descending and is forcing the air out through a pipe 53. When the bell approaches the limit of its downward movement, the cord 51 will operate on the lever 44 of the valve mechanism and will shift the valve, the weighted arm of the valve operating lever being moved across the vertical plane of the lever pivot and the weight 100 46 then acting to complete the valve movement, so that the valve is shifted to the position shown in Fig. 3. During this downward movement of the bell, the water is gradually forced out from the cylinder 17 105 and passes through the pipe 30 and port 41 of the valve 38 to the discharge pipe 33. 110

After the valve has been shifted to the position shown in Fig. 2, the water under pressure entering through the pipe 32 flows through the port 39 and valve 37 to the chamber 28, thence through pipe 30 to the lower end of the cylinder 17 and elevates the piston therein, causing the air bell to move upward to its fullest extent and draw in air through the check valve 21. The other bell 10 is, also, descending, and the water is flowing out from the cylinder 18 through the pipe 29, the chamber 27, and through port 42 of valve 38 to the discharge pipe 33, the air in said bell being forced outward through the pipe 54.

15 I claim:—

1. In a hydraulic air pump, the combination of a casing provided with a pair of pressure chambers and inlet and outlet connections, a valve adjacent said inlet connection and arranged to admit fluid pressure to one of said chambers, and a second valve adjacent said outlet and arranged to permit fluid pressure to pass from the other of said chambers, said valves being provided with a pair of ports having inlet ends in juxtaposition and on the same face of the valve and outlet ends opening from opposite ends of said valve.
- 20 2. In a hydraulic air pump, the combination of a casing provided with a pair of pressure chambers and inlet and outlet connections, valves each provided with a pair of ports held to slide opposite said connection and each having inlet ends in juxtaposition and on the same face of the valve, and outlet ends opening from opposite ends of said valve to permit communication through one of said chambers.
- 30 3. In a hydraulic air pump, the combination of a casing provided with a pair of pressure chambers and inlet and outlet connections, said pressure chambers being separated by a partition provided with a pair of 35 openings extending from one of said chambers to the other and in line with said inlet and outlet, a pair of slide valves arranged to move in said openings, each of said valves being provided with a pair of ports having inlet 40 ends in juxtaposition and on the same face of the valve, and outlet ends opening from opposite ends of the said valve to permit the passage of fluid pressure to one of said chambers, and the passage of fluid pressure from 45 the other of said chambers, and means for shifting the position of said valves simultaneously and reversing the flow of said fluid pressure.
- 50 4. In an apparatus of the character described the combination of a pair of alternately operable air pumps, each including a movable bell, fluid pressure cylinders, pistons arranged therein and connected to the

55 bells for elevating the latter, a valve chamber having fluid pressure and exhaust ports, connections between said valve chamber and the two cylinders, a pair of valves each provided with a pair of ports having inlet ends in juxtaposition and on the same face of the valve, and outlet ends opening from opposite 60 ends of the said valve arranged in said chamber and controlling the flow of the actuating fluid to and from the two cylinders, means under the control of the bells for shifting the valves, and air pipes leading from the bells. 70 75

5. In an apparatus of the character described the combination of a pair of alternately operable air pumps, each including a movable bell, a pair of cylinders, pistons arranged therein and connected to the bells, a 80 valve casing having fluid pressure and exhaust ports, connections between said valve chamber and the cylinders, a pair of valves each provided with a pair of ports having inlet ends in juxtaposition and on the same 85 face of the valve, and outlet ends opening from opposite ends of the said valve arranged in said chamber and controlling the flow of the fluid to and from the cylinders, a weighted lever connected to the two valves, flexible 90 connections between said lever and the movable bells, and air pipes leading from the air pumps.

6. In an apparatus of the character described the combination of a pair of alternately operable air pumps, each including a movable bell, a pair of cylinders arranged in the air pump, pistons disposed in the cylinders and connected to the bells, a valve casing having inlet and exhaust ports for a fluid under pressure, a central block dividing the same into upper and lower chambers, a pair of slide valves arranged in the valve casing, and each provided with a pair of ports having inlet ends in juxtaposition and on the same face of the valve, and outlet ends opening from opposite ends of the said valve, one of the valves controlling the admission and the other the exhaust of the fluid, pipes connecting the chambers to the lower ends of the cylinders, a pivotally mounted three armed lever, two of the arms being connected to the valve and the other arm being rigid to complete the valve movement, flexible connections between the lever and movable bells, 100 air pipes leading from the air pump, and a connection between the exhaust port of the valve casing and the air pump tanks. 110 115

In testimony that I claim the foregoing as my own, I have hereto affixed my signature 120 in the presence of two witnesses.

ALBERT S. GRAY.
